Primary Examiner — Marissa J Cash*(74) Attorney, Agent, or Firm* — Brian Roffe**CLAIM**

The new, original and ornamental design for a device for smoking or vaporizing, as shown.

DESCRIPTION

FIG. 1 is a top, perspective view of a smoking device showing my new design;

FIG. 2 is a front view thereof;

FIG. 3 is a rear view thereof;

FIG. 4 is a right side thereof;

FIG. 5 is a left side thereof;

FIG. 6 is a top view thereof; and,

FIG. 7 is a bottom view thereof.

The broken lines immediately adjacent the claimed areas represent the bounds of the claimed design while all other broken lines are directed to environment and are for illustrative purposes only; the broken lines form no part of the claimed design.
